STOCKING

Max Fisher, Lower Alsace Township, Berks County, and George J. Eligman, Mount Penn, Pa.

Application June 11, 1953, Serial No. 25,437

Term of patent 14 years

(Cl. D47—7)

To all whom it may concern:

Be it known that we, Max Fisher and George J. Eligman, both citizens of the United States, respectively residing at Lower Alsace Township, county of Berks, State of Pennsylvania, and Borough of Mount Penn, county of Berks, State of Pennsylvania, have invented a new, original, and ornamental Design for Stocking, of which the following is a specification, reference being had to the accompanying drawings forming a part thereof, wherein:

We claim:

The ornamental design for a stocking, as shown.

MAX FISHER.
GEORGE J. ELIGMAN.
